UNITED STATES PATENT OFFICE.

GEORGE A. BLAKE, OF NEW BEDFORD, MASSACHUSETTS.

VALVE.

No. 927,100.

Specification of Letters Patent.

Patented July 6, 1909.

Application filed January 22, 1907. Serial No. 353,540.

To all whom it may concern:

Be it known that I, GEORGE A. BLAKE, a citizen of the United States, and resident of New Bedford, Bristol county, State of Massachusetts, have invented certain new and useful Improvements in Valves, of which the following is a specification.

The present invention relates to improvements in valves particularly adapted for use with fluid under relatively high pressure and the primary object of the invention is to provide a valve of this character that can be more readily repaired if necessary than valves of the same type commonly in use.

A further object of the invention is to provide such a valve which will be free from any objectionable noise or "water hammer" and will operate as quietly as do valves acting under ordinary pressures.

In the accompanying drawing, Figure 1 is a sectional view through a faucet having a valve constructed in accordance with this invention, showing the valve closed; Fig. 2 is a similar view showing the valve lifted from its seat; Fig. 3 is a sectional view through a tank valve embodying the invention.

Referring particularly to Figs. 1 and 2, the valve casing 1 is provided at its inlet end with a threaded section 2, by means of which it may be suitably connected with a supply pipe; and has an interior valve seat 3 with which co-operates the valve 4. The casing 1 is made of such form that chambers 5, 6, are formed on opposite sides of the fluid passage 35 and the valve seat, the outer end of the chamber 5 being closed by a removable cap 7; and the outer end of the chamber 6 having therein an aperture through which the stem 8 of the valve passes. An operating lever 9 is suitably connected with the lower end of the valve stem which projects beyond the casing and by means of said lever the valve may be lifted from its seat to open the fluid passage through the casing 1. As shown 45 said lever is fulcrumed at 10 upon the valve casing and is provided with two slots or apertures 11, 12, through which extend, respectively, the lower end of the valve stem and the curved discharge or outlet end of the 50 valve casing or faucet body. The portion of the valve stem that extends through said operating lever is reduced in diameter and a pin or key 13 extends transversely through the same below the lever. The stem of the 55 valve extends above the seat 3 and on such upward projecting section is screwed a circu-

lar nut 14 which thus forms a part of the valve, a suitable washer 15 being interposed below the lower face of said nut and the valve head 4. The enlarged upper portion of the valve extends into the chamber 5 in the valve casing but does not fit so closely therein as to prevent the fluid from passing into the chamber, above the valve and thereby the latter is held against its seat when closed by the full fluid pressure. The upward movement of the valve, when lifted by the lever 9, is cushioned by the air and water pressure within said chamber 5. A piston 16 is secured, or formed, upon the valve stem below the seat 3 and fits closely within the chamber 6, whereby there is provided an air cushion for resisting the closing movement of the valve and preventing such a sudden downward movement as to cause an objectionable noise. The piston 16 is of such diameter that it can pass through the opening in the valve seat and therefore in case it is desired to repair or replace the valve it is only necessary to remove the cap 7 and disconnect the lever 9 from the stem 8 when the entire valve can be lifted from the casing. By this construction, therefore, it is possible to inspect or entirely remove the valve without disconnecting the casing or detaching the several parts of the valve itself.

In the form of the invention shown in Fig. 3, the valve casing is provided with a chamber 17 above the valve similar to the upper chamber of the valve casing shown in Figs. 1 and 2, said chamber being closed by a detachable cap 18; and the valve is held closed by the pressure of fluid in the casing. The stem 19 in this embodiment of the invention is engaged with an arm 20 on a lever 21 having formed therein two sockets with either of which the threaded stem 22 of an ordinary float lever may be connected. When the valve is employed with a tank in which the supply pipe enters the top, said float stem will be connected, as shown in Fig. 3. If, however, the supply pipe enters the tank from the bottom, in which case the valve casing will extend vertically, said stem 22 will be secured in the other socket of the lever 21.

It will be seen that the fluid does not pass directly through the chamber in which the valve head moves, although the full pressure of the fluid is utilized to move the valve toward and hold it against the valve seat, such closing action of the valve being also assisted by its weight, or gravity, so that it is

well adapted for either low or high pressure service.

In the form of the invention shown in Figs. 1 and 2, the piston 16 and air chamber 5, 6 not only act as a check to the valve when closing but the piston also prevents any serious leakage, as the direct pressure of the fluid is broken by striking the upper face of the piston.

10 Having described my invention what I claim and desire to secure by Letters-Patent is,

The combination of a valve casing having a horizontal valve seat formed therein, and provided with two chambers 5, 6, arranged respectively above and below said valve seat, a valve stem extending through the chamber 6 and the valve seat, a valve mounted on the upper end of said stem and having its upper end projecting into the upper chamber 5, a 15 removable closure for the chamber 5, a pis-

ton secured to the valve stem within the chamber 6, the parts being so arranged and proportioned that when the valve is closed the full pressure of fluid controlled by the valve acts upon the upper surface thereof and when the valve is open the fluid pressure exerted in opposite directions on the valve and piston is substantially equal and the valve and piston fitting their respective 20 chambers so closely that no special packing is required, and means for raising the valve from its seat and connected with the valve casing and valve independently of the removable closure for the chamber 5. 35

In testimony whereof I affix my signature in presence of two witnesses.

GEORGE A. BLAKE.
